UNITED STATES PATENT OFFICE.

WILLIAM S. WITTEN, OF CHICAGO, ILLINOIS.

LATCH.

Application filed April 5, 1920. Serial No. 371,188.

To all whom it may concern:

Be it known that I, WILLIAM S. WITTEN, a citizen of the United States, and a resident of Chicago, in the county of Cook and 5 State of Illinois, have invented certain new and useful Improvements in Latches, of which the following is a specification, reference being had to the accompanying drawings.

10 My invention relates to latches of the type comprising a latching member in the form of a latch bolt carried at the lower end of a pendulous bar, and it is designed for use with doors or gates of all kinds. The object 15 of my invention is to provide a latch of that type with a new and improved case which will support the latching member against lateral strains, and will be so constructed that it may be mounted on a door 20 at a considerable distance from the edge thereof without impairing its efficiency in that respect, and which will also serve not only to protect the latch but also to insure its proper operation. I accomplish this object 25 as illustrated in the drawings and as hereinafter described. What I regard as new is set forth in the claims.

In the drawings,—

Fig. 1 is a face view of my improved latch 30 in position upon a door, a small portion only of which is shown, and arranged to co-operate with a suitable keeper on the adjacent door-post;

Fig. 2 is an enlarged view, being substantially a horizontal section taken on line 2—2 of Fig. 1;

Fig. 3 is also an enlarged view being substantially a vertical section taken on line 3—3 of Fig. 1;

Fig. 4 is a perspective view of my improved latch in position on a door, some parts being broken away in order better to illustrate the construction; and

Fig. 5 is a view showing the latch equipped with an operating device and mounted on a small door of an out-building.

Referring to Figs. 1 to 4 which show the preferred form of my device, 10 indicates a door upon which my improved latch is mounted so as to co-operate with a suitable keeper 11 mounted upon a door-post 12. The latching member comprises a latch-bolt 13 carried at the lower end of a pendulous bar 14, so that it forms therewith an inverted T-shaped

member. The parts are preferably integral 55 with each other. The pendulous bar 14 is mounted at its upper end upon a rock-shaft 15, the opening through the bar being angular in shape to conform to the cross-section of the rock-shaft. A set screw 16 is used 60 for securing the bar in position upon the shaft. A handle 17 is provided upon one end of the rock-shaft 15 by bending the shaft substantially at right angles at one end portion. The opposite end of the shaft 65 15 is provided with a knob or handle 18 of any approved type fixedly secured upon the shaft.

For protecting the operating parts from the weather, supporting the bolt against 70 lateral strains, and for controlling its operation, I have provided an improved form of casing comprising two casing members 19 and 20, the latter of which is mounted telescopically within the other member. By 75 making the side walls of the two members 19 and 20 of appropriate width with respect to each other as is best shown in Figs. 2 and 3, a very strong and effective casing is provided adapted to be held firmly in position by the securing means which, in the construction illustrated, is in the form of screws 21. As is clearly shown in Fig. 3, the rock-shaft 15 is revolvably mounted in the oppositely-disposed walls of the casing by 80 means of bushings 22.

It is desirable both from the standpoint of convenience and efficiency, to have the latch-operating handle or lever positioned a short distance back of the edge of the door, 90 but it is necessary that the outer end of the bolt when it is in its operative position project far enough beyond the outer edge of the door to engage the keeper. It is also necessary that means be provided for limiting the outward movement of the bolt, and that the bolt be supported against lateral strains. These requirements are all met by constructing the case in a special manner which will now be described. As best shown in Fig. 1, the outer marginal wall of the case is vertical and parallel with the bar 14, which, when the bolt is in operative position, is in contact with said wall, so that the wall serves as a stop to limit outward movement 95 of the bolt. Said wall does not, however, extend down to the bolt, but at a point a short distance above it it is provided with 100 105

an extension 23 through which one of the screws 21 passes. By means of this extension the case provides a very strong support for the bolt against lateral strains, as the extension approaches closely to the edge of the door and permits the screws which secure the lower end of the case to be placed quite a distance apart longitudinally of the bolt. One of the screws is placed above and 10 the other below the bolt, as shown in Fig. 1, and consequently the bolt is well braced against the strains to which it is subjected while its capacity to swing freely is not interfered with. This arrangement also 15 relieves the upper end of the casing from twisting strains. The screw 21 which is placed back of the bar 14 and above the bolt serves as a limit stop for determining the extent to which the bolt may be withdrawn 20 into the case and also causes the bolt to rebound to its operative position when it is swung back sharply into the case.

In the modified arrangement shown in Fig. 5 the handle portion 17 of the rock-shaft 15 is omitted and a cable 24 is used 25 for moving the latch bolt inward out of operative position. In the illustrated arrangement the cable 24 extends from the latch bolt over a small pulley 25 mounted in 30 suitable position on the door 26 so that by pulling on the cable the bolt may be withdrawn into the case. When the tension on the cable is relieved the bolt is returned by 35 gravity to its operative position.

It will be understood that the principal support for the latch-bolt 13 is provided by those parts of the walls of the casing immediately adjacent to the screws 21, from 40 which it will be appreciated that the distance at which such screws are located from each other is of importance in the matter of the strength of the support provided, inasmuch as a much stronger support is attained as such screws are moved farther 45 apart. In this particular then the provision of the extension 23 is important, since by the use of this extension I am enabled to place the screws 21 at the lowermost portion of the casing at a considerably greater distance apart without the necessity for employing the useless metal involved in making the casing as a whole flush with the edge 50 of the door. By the use of this expedient, I am enabled to obtain the requisite reinforcement of the latch-bolt without the use 55 of any additional means for strengthening the casing walls adjacent to the position of the latch-bolt.

What I claim as my invention and desire 60 to secure by Letters Patent, is—

1. A latch comprising a casing, a pendulous inverted T-shaped bar pivotally supported at its upper end in said casing, a rock-shaft upon which said bar is fixedly 65 mounted, a stop carried by said casing

adapted to engage said bar to limit its movement in one direction, and a handle in the form of an angularly-disposed lever fixedly connected with said rock-shaft for actuating said pendulous bar. 70

2. A latch comprising a casing formed of two members having telescopic engagement with each other, means for securing said two members firmly together, a pendulous bar mounted in said casing, and a horizontally-disposed latch-bolt mounted on the lower end of said pendulous bar and movable freely between and supported against lateral strains by the oppositely-disposed walls of said casing, said latch bolt being arranged 80 normally to project beyond said casing and being adapted to be retracted thereinto.

3. A latch comprising a casing formed of two members having telescopic engagement with each other, a pendulous bar mounted in 85 said casing, a horizontally-disposed latch-bolt mounted on the lower end of said pendulous bar and movable freely between and supported against lateral strains by the oppositely-disposed walls of said casing, said latch bolt being arranged normally to project beyond said casing and being adapted to be retracted thereinto, and screws securing 90 said two casing members together both above and below said latch-bolt. 95

4. A latch comprising a casing adapted to be secured to a door a short distance back from the edge thereof, a pendulous bar mounted in said casing, a horizontally-disposed latching-bolt mounted on the lower end of said pendulous bar and movable freely between the oppositely-disposed walls of said casing, and an extension from the edge of said casing substantially to the edge 100 of the door adapted to support the latching-bolt adjacent to the co-operating keeper. 105

5. A latch comprising a casing adapted to be secured to a door a short distance back from the edge thereof, a pendulous bar mounted in said casing, a horizontally-disposed latch bolt mounted on the lower end of said pendulous bar and movable freely between the oppositely-disposed walls of said casing, said latch bolt being arranged 110 normally to project beyond said casing and being adapted to be retracted thereinto, an extension from the edge of said casing substantially to the edge of the door, and a screw extending transversely through the casing adjacent to said extension for resisting lateral strains imposed upon the projecting end of said latch bolt. 115

6. A latch comprising a casing formed of two members having telescopic engagement 125 with each other, a pendulous bar mounted in said casing, a horizontally-disposed latch bolt mounted on the lower end of said pendulous bar and movable freely between the oppositely-disposed walls of said casing, said latch bolt being arranged normally to pro- 130

- ject beyond said casing and being adapted to be retracted thereinto, an extension from the edge of said casing formed integral with the casing members and comprising means 5 for holding the extension walls at the desired distance apart, and means for securing said extension parts firmly together for providing a support for said latch-bolt against lateral strains.
- 10 7. A latch comprising a casing formed of two members, a pendulous bar mounted in said casing, a horizontally-disposed latch-bolt mounted on the lower end of the pendulous bar and movable freely between and supported against lateral strains by the oppositely-disposed walls of said casing, said latch bolt being arranged normally to project beyond said casing and being adapted to be retracted thereinto, a screw securing 15 said two casing members together at the front edge portion of said casing above said latch-bolt, a second screw securing said two casing members together at the rear edge portion of the casing below said latch-bolt, and means carried by the casing adjacent to 20 said screws respectively for holding the walls thereof spaced apart.
8. A latch comprising a casing formed of two members, a pendulous bar mounted in said casing, a horizontally-disposed latch-bolt mounted on the lower end of the pendulous bar and movable freely between and supported against lateral strains by the oppositely-disposed walls of said casing, said latch bolt being arranged normally to project beyond said casing and being adapted to be retracted thereinto, a screw securing 25 said two casing members together at the front edge portion of said casing above said latch-bolt, a second screw securing said two casing members together at the rear edge portion of the casing below said latch-bolt, and means carried by the casing adjacent to 30 said screws respectively for holding the walls thereof spaced apart.
